Primary Examiner—Charles A. Rademaker*Assistant Examiner*—Charles Hanson*(74) Attorney, Agent, or Firm*—Elsie C. Turner(57) **CLAIM**

The ornamental design for a bus tray, as shown and described.

DESCRIPTION

FIG. 1 is a perspective view of a bus tray showing my new design;

FIG. 2 is a side elevation view thereof, the opposite side being a mirror image;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view of a modified embodiment thereof;

FIG. 8 is a side elevation view thereof, the opposite side being a mirror image;

FIG. 9 is front elevational view thereof;

FIG. 10 is a rear elevational view thereof; and,

FIG. 11 is a top plan view thereof, it being understood that the bottom plan view is exactly the same as FIG. 6.
